UNITED STATES PATENT OFFICE.

ELMER L. SCHUMACHER, OF SOUTHBIDGE, AND WILLIAM H. BOUTELLE, OF STURBRIDGE, MASSACHUSETTS, ASSIGNORS TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,415,612.

Specification of Letters Patent.

Patented May 9, 1922.

Application filed November 25, 1921. Serial No. 517,722.

To all whom it may concern:

Be it known that we, ELMER L. SCHUMACHER and WILLIAM H. BOUTELLE, citizens of the United States, residing at Southbridge and Sturbridge, respectively, in the county of Worcester and State of Massachusetts, have invented certain new and useful Improvements in Ophthalmic Mountings, of which the following is a specification.

10 This invention relates to improvements in ophthalmic mountings and has particular reference to what is termed a combination mounting, that is to say, a mounting made up of a combination of metallic and non-metallic parts.

One of the principal objects of the present invention is the provision of a novel and improved construction of frame and method of producing the same which shall cause the 20 frame to present the appearance of an all zylonite or composition structure and at the same time possess all the advantages inherent in an all metal construction.

A further object of the present invention is the provision in a construction of this character of a novel and improved means for separably uniting the split ends of the frame in a manner to render the joint substantially invisible and so that the continuity of the end piece or other parts will be unbroken as viewed from the front but in which the frame may be readily opened for insertion or removal of a lens.

A further object of the present invention is the provision of a novel and improved end piece and frame connection and method of producing the same.

Other objects and advantages of the present invention should be readily apparent by 40 reference to the following specification taken in connection with the accompanying drawings, and it will be understood that we may make any modifications in the specific details of construction and method of producing the 45 same within the scope of the appended claims without departing from or exceeding the spirit of our invention.

Figure I represents a front view of a frame embodying these improvements.

50 Figure II represents a plan view thereof.

Figure III represents a fragmentary sectional view of the metallic parts of the frame as on the line III—III of Figure II.

Figure IV represents an end view of the end piece covering blank.

Figure V represents a sectional view on the line V—V of Figure IV.

Figure VI represents an end view illustrating a further step in our process.

Figure VII represents a plan view of the 60 construction shown in Figure VI.

Figure VIII represents a view taken as on the line VIII—VIII of Figure III.

Figure IX represents a similar view showing the member of Figure VII applied. 65

Figure X represents a view of a subsequent step in the process or method of manufacture.

Figure XI represents a sectional view of the complete frame as on the line XI—XI of 70 Figure II.

In the drawing, in which similar characters of reference are employed to denote corresponding parts throughout the several views, the numeral 1 designates the metallic 75 bridge member having the central non-metallic covering 2 formed thereon and having secured to each end a metallic frame or rim member 3. One of these members 3 is provided with a slide block end piece 4 having the slot 5 formed therein to receive the metallic butt 6 of the composition temple 7. This block 4 is further formed centrally thereof with the recess 8 in which fits the end piece plate 9 of the opposite end of the 85 frame 3, the member 9 fitting down into the socket 8 so as to be invisible when the parts are viewed from the front and being retained in position as by the screw 10.

As has been previously mentioned, the 90 purpose of the present invention is to provide a mounting which shall present the general appearance of the old and well-known all shell or composition frame, but with the increased advantages of the metallic frame as well. In the accomplishment 95 of this result we, therefore, wish to cover the metallic end piece 4 with a suitable coating of zylonite or other composition material which may be secured in place in a num- 100

ber of ways, as by spraying, dipping or cementing thereon, or more particularly and preferably by the hereinafter described method. This method consists in taking a 5 piece of rod stock 11 of the desired composition material and centrally boring it as at 12, as indicated in Figure V. The material is then flattened as in Figure VI and notched as at 13 in Figure VII. After this 10 the blank 11 is slipped over the end piece block 4 as shown in Figure IX, the recess or notch 13 serving to fit up against and around the frame 3. The member 11 is then shaped by pressure, cutting, or both, to 15 closely conform to the block 4, and is also cut away to provide the lip or flap 14 corresponding in size and shape to the free or exposed portion of the plate 9. It will be understood that on account of the shape of 20 the end piece block 4 the member 11 when pressed and formed therearound will closely adhere thereto and be retained in place thereon. To assist the union of the parts, however, we preferably before placing in 25 position the member 11, apply either to the interior thereof, or to the block 4, or to both, a suitable substance which will render the surface of the composition material soft or tacky and cause it to closely and tightly 30 adhere to the block 4 and the separable block member 9. The parts having been thus secured a suitable slot as at 15 is formed in the member 11 to receive the temple butt 6 and a composition covering or rim 16 is 35 placed around the metallic rim 3 and secured by cement or the like, as at 17 and 18, to the lip section 14 and the main body section 11 of the end piece covering, respectively. This uniting of the end piece covering and the outer rim serves to securely connect and hold the parts together, if desired the outer rim being also cemented to the rim 3 to aid in uniting the parts and rendering them more secure. 40

45 It will thus be seen that we have provided a novel and improved construction in which the end piece is covered with a zylonite coating entirely unbroken as viewed from the front, but in which the frame is itself split 50 at the end piece so that by loosening of the screw 10 the same may be opened, while tightening of the screw 10 serves to hold down the portions 9 and 14 and thus the ends of the metallic and non-metallic rims 55 to the main portion of the end piece with an invisible joint.

We claim:

1. A frame of the character described comprising a metallic bridge and eye wire, said 60 eye wire being split at the outer side, an end piece member carried by one end of the split eye wire and having a recess formed therein, a connecting plate carried by the other end of the eye wire and of size to fit within the 65 recess, and a unitary composition frame

member having a portion enclosing the end piece, a second portion encircling the metallic rim, and a terminal flap overlying the connecting plate on the opposite end of the metallic rim and when closed making flush 70 joint with the end piece covering to substantially conceal the union of the split ends of the frame.

2. In a device of the character described, the combination with a solid block metallic 75 end piece of a split metallic rim carried thereby, a composition covering for said rim and end piece, said end piece having a socket formed therein and a connecting member on the opposite end of the rim, said connecting 80 member comprising a metallic plate adapted to fit within the socket, and a non-metallic cover portion for concealing the socket.

3. The process of forming an ophthalmic mounting consisting in shaping a metallic 85 end piece, forming a piece of non-metallic stock with a socket, forcing the end piece into the socket and shaping the non-metallic material to conform to the end piece.

4. The process of forming an ophthalmic 90 mounting consisting in shaping a metallic end piece, forming a piece of non-metallic stock with a socket, forcing the end piece into the socket and shaping the non-metallic material to conform to the end piece, and 95 slotting the shaped end piece covering to receive a temple butt.

5. The process of forming an ophthalmic mounting consisting in shaping a metallic end piece, forming a piece of non-metallic 100 stock with a socket, forcing the end piece into the socket, shaping the non-metallic material to conform to the end piece, and cutting a flap from one side of the covering to form a connecting plate receiving socket. 105

6. The process of forming an ophthalmic mounting consisting in shaping a metallic end piece, forming a piece of non-metallic stock with a socket, forcing the end piece into the socket, shaping the non-metallic 110 material to conform to the end piece, slotting the shaped end piece covering to receive a temple butt, and cutting a flap from one side of the covering to form a connecting plate receiving socket. 115

7. The process of forming a composition ophthalmic mounting consisting in forming a solid metallic end piece with a connection receiving socket, forming a connection to fit within the socket, applying a continuous 120 non-metallic covering to the end piece and connecting member while within the socket, and subsequently severing the composition covering to release the connection and attached covering therefor. 125

8. The process of forming a composition ophthalmic mounting consisting in forming a solid metallic end piece with a connection receiving socket, forming a connection to fit within the socket, applying a continuous 130

non-metallic covering to the end piece and connecting member while within the socket, subsequently severing the composition covering to release the connection and attached covering therefor, and securing the termini of a split non-metallic rim to the end piece covering and connection covering respectively.

In testimony whereof we have affixed our signatures in presence of two witnesses.
